UNITED STATES PATENT OFFICE

120,350

DESIGN FOR A BIRD FEEDER

Fayette Moore, Cedar Rapids, Iowa

Application February 8, 1939, Serial No. 82,869

Term of patent 7 years

To all whom it may concern:

Be it known that I, Fayette Moore, a citizen of the United States, residing at Cedar Rapids, in the county of Linn and State of Iowa, have invented a new, original, and ornamental Design for Bird Feeders, of which the following is a specification, reference being had to the accompanying drawing, forming part thereof.

Fig. 1 is a perspective view of a bird feeder, showing my new design; and Fig. 2 is a side elevational view thereof.

I claim:

The ornamental design for a bird feeder, as shown.

FAYETTE MOORE.
